UNITED STATES PATENT OFFICE.

FRANK M. OSBORNE, OF ANACONDA, MONTANA.

PISTON RING.

1,421,295.

Specification of Letters Patent. Patented June 27, 1922.

Application filed April 27, 1921. Serial No. 464,781.

To all whom it may concern:

Be it known that I, FRANK M. OSBORNE, a citizen of the United States of America, residing at Anaconda, in the county of Deer-lodge and State of Montana, have invented new and useful Improvements in Piston Rings, of which the following is a specification.

The object of the invention is to provide a simple and efficient piston ring for use in connection with engines of the explosion and other types for insuring a pressure tight bearing against the surface of the cylinder wall, and more especially to provide a one-piece split ring of even weight or thickness throughout as distinguished from those rings now in common use which are of a variable or graduated thickness from the extremities toward an intermediate point; and with this object in view the invention consists in a construction and combination of parts of which a preferred embodiment is shown in the accompanying drawings, wherein:—

25 Figure 1 is a plan view of a piston ring embodying the invention applied in the operative position to a piston, the latter being shown in section.

Figure 2 is a side view of the same showing the preferred form of joint.

Figure 3 is a transverse sectional view thereof.

The ring proper as shown at 10 is of the single piece split ring type preferably having a step lap joint 11 between its extremities, the ring being of uniform gauge or of even thickness and width throughout but with a cross sectionally V-shaped or grooved inner surface as indicated at 12, and in cooperative supplementally expansive relation with the body portion of the ring is a steel

wire expander 13 also of ring form but of sinuous contour providing a series of oppositely directed arches of which the bases bear respectively against the inner surface 45 of the ring and the bottom of the ring groove 14 in the piston 15. The crowns or apexes of the arches of the expander bear in the annular angle formed by the cross sectionally V-shaped seat in the inner surface of 50 the body portion of the ring so as to maintain a uniform relative position and prevent lateral displacement of the expander, and by reason of the uniform expansive effect of the expander the body portion of 55 the ring is held uniformly or with a uniform pressure against the surface of the cylinder wall without necessitating as in the ordinary practice the thickening of the ring from its extremities or joint toward a point diametri- 60 cally opposite to the joint.

Having described the invention, what is claimed as new and useful is:—

A device for the purpose indicated consisting of a split ring having overlapping 65 extremities, and a spring expander formed with alternate oppositely directed arches for bearing contact against the opposed surfaces of the body portion of the ring bottom and the ring groove of a piston, the spring being 70 of materially reduced width with respect to the ring and the latter being provided with a seat on its inner periphery consisting of a cross sectionally V-shaped groove in which the apexes of the arches engage to preclude 75 lateral displacement of the expander and maintain a uniform relative position of the same.

In testimony whereof he affixes his signature.

FRANK M. OSBORNE.
